LIQUID DISPENSING DEVICE

George B. Davis, Jr., Washington, D. C.

Application June 22, 1937, Serial No. 149,762

4 Claims. (Cl. 221—84)

This invention relates to a liquid dispensing device designed primarily for use with the type of measuring apparatus used at filling stations for dispensing liquid fuel to automotive vehicles, but it is to be understood that the device, in accordance with this invention, is for use in any connection for which it may be found applicable, and the invention has for its object to provide, in a manner as hereinafter set forth, a device of the type referred to so constructed and arranged to provide for a variable flow of the liquid therefrom when occasion requires.

A further object of the invention is to provide, in a manner as hereinafter set forth, a device of the type referred to which may be expeditiously secured to the regular standard flexible hose leading from the liquid measuring apparatus.

A further object of the invention is to provide, in a manner as hereinafter set forth, a device of the type referred to including a nozzle coupling portion, a combined valve chamber and handle part and a shiftable spring controlled manually operated valve controlling means depending from said part and arranged forwardly of the front 25 of the handle for controlling the dispensing action of the device.

Further objects of the invention are to provide, in a manner as hereinafter set forth, a device for the purpose referred to which is simple in its construction and arrangement, strong, durable, compact, readily assembled, thoroughly efficient in its use, conveniently and expeditiously operated to provide a liquid dispensing function and comparatively inexpensive to manufacture. The 35 channel is of large size at the inlet end where it connects with the supply pipe and gradually decreases in size throughout its length to the valve below described, and just beyond the valve is also of small size, from whence it is greatly and 40 immediately enlarged and so continues to the exit. The result of this structure is that toward the center of the device the flow is choked back and decreased in volume, but due to the enlargement of the exit a free passage is provided and 45 the flow not forced out but allowed to move quietly whereby turbulence and splashing is prevented.

To the above ends essentially and to others which may hereinafter appear, the invention 50 consists of the novel construction, combination and arrangement of parts as will be more specifically described and illustrated in the accompanying drawing wherein is shown an embodiment of the invention, but it is to be understood that changes, variations and modifications may

be resorted to which fall within the scope of the invention as claimed.

In the drawing:

Figure 1 is a side elevation of the device installed with respect to a liquid conducting line leading from a source of supply, 5

Figure 2 is a vertical sectional view of the device with the nozzle element thereof removed,

Figure 3 is a section on line 3—3, Figure 2, and 10

Figure 4 is a top plan view of the controlling lever partly in section.

The device includes a casting 1 formed of any suitable material channelled from end to end thereof. The casting 1 consists of a nozzle coupling portion 2, a valve chamber portion 3 and a handle or hand grip forming portion 4. The portion 3 couples the portions 2 and 4 together and is substantially of elbow-shape in lengthwise section. The portion 2 is straight. The 15 portion 3 inclines rearwardly and depends from the rear end of the portion 3. The channel which extends from end to end of the casting 1 has the part 5 thereof arranged in portion 4, part 6 thereof arranged in portion 3, the lip or part 7 thereof arranged in portion 3 and the part 8 thereof arranged in the portion 2. The part 8 merges into the forward end of the part 7 and the rear end of the latter merges into the forward end of the part 6. The upper end of part 20 5 merges into the other end of part 6. The part 5 is disposed at an inclination with respect to the part 6. The latter is of curved contour and has its forward portion arranged above the rear of part 7. The part 8 is straight and opens at 25 the rear end of its bottom into part 7. The part 8 is of greater diameter than the parts 5, 6 and 7. The portion 3 of casting 1 has an integral depending web 9 between the parts 10 and 11 of such portion. The web 9 aligns with the longitudinal median of portion 3 and is spaced from the side faces of the latter. The forward end of the wall of part 6 of the channel is bevelled as at 30 12 to provide a valve seat arranged at the top of part 7 of the channel and within the portion 3 of the casting. Directly below and spaced from the seat 12 the part 10 of the portion 3 of the casting is formed with a vertically disposed valve chamber 13 which opens into the part 7 of the channel and also opens at the bottom of the 35 part 10 of portion 3 of the casting. The outer portion of the wall 14 of valve chamber 13 is threaded as at 15 and engaging therewith is an outer packing gland 16 formed at its inner end with an inwardly extending annular flange 17 40

45

50

55

55

and at its outer end with an outwardly directed annular flange 18. The gland 16 is interiorly threaded and engaging therewith is a peripherally threaded inner packing gland 19 having an external flange 20 abutting flange 18.

Extending through the glands 16 and 19 is a stem 21 formed with a circular head 22 of a diameter to snugly engage the wall 14 of valve chamber 13. Fixed to the top of head 22 is a bevelled disc-shaped valve 23 adapted to engage the seat 12 for the purpose of closing part 6 of the channel to part 7 of the latter. When the valve 23 is off its seat, communication is established between the parts 6 and 7 of the channel 15 of the casting. The stem 21 is of a length to project beyond the gland 19 and carries at its outer end a diametrically extending pin 24. Interposed between the flange 17 of gland 16 and the inner end of gland 19 and surrounding stem 21 is a packing 25.

The device includes a nozzle 26 which is interiorly threaded and engages with the peripheral threads 27 formed on the portion 2. The latter has an annular stop or rib 28 on its periphery on 25 the inner end of the threads 27.

The device includes a shiftable spring controlled manually operated controlling lever 29 for the valve structure consisting of the stem 21, head 22 and disc 23. The lever 29 is of angle 30 form and consists of an upper horizontally extending leg 30 and a vertically disposed leg 31 depending from the inner end of the leg 30. The leg 30 has a bifurcated forward end 32 provided with aligning slots 33 and at its rear end is formed 35 with a pair of ears 34 having aligned openings 35. The inner face of the leg 31 is formed with a groove 36 extending lengthwise thereof. The pin 24 projects laterally in opposite directions from the stem 21 and is slidably mounted in the slots 33. The lower end of the stem 21 is positioned in the bifurcated end 32 of the leg 30. The web 9 is formed with an opening 37 which aligns with the openings 35. A pin 38 extends through the aligning openings 35, 37 for pivotally 40 connecting the rear end of the leg 30 to the portion 3 of the casting 1.

The forward side of the portion 4 of casting 1 has a groove 39 lengthwise thereof and which opposes the groove 36. Arranged between the leg 31 and the front of the portion 4 of casting 50 1 is a spring 40 formed of a looped part 41 and a pair of end parts 42, 43 extending in opposite directions with respect to each other. The end part 42 bears against the wall of the groove 36. The end part 43 bears against the wall of the 55 groove 39. The spring 40 functions to normally maintain the valve structure in position to shut off communication between parts 6 and 7 of the channel in casting 1.

60 The valve structure is slidably connected to the lever 29 or in other words, there is a loose sliding connection between the lever 29 and the lower end of the stem 21. When rearward pressure is exerted against the leg 31 of lever 29 the leg 30 is lowered which in turn will force the valve structure downwardly and the extent of the shift will provide for varying the flow of the discharge 65 of the liquid from the casting 1 into the nozzle 26.

With reference to Figure 1 a fluid conducting 70 line is indicated at 44 and is attached to the portion 4 of the casting 1.

The disc 23 is to be constructed of any suitable material and is anchored to the head 22 by the holdfast means 45.

75 What I claim is:

1. In a device for the purpose set forth, a casting including an intermediate portion, a forward end portion and a rear end portion arranged in depending relation with respect to said intermediate portion and providing a hand grip, said casting being formed with a channel from end to end thereof, a valve seat on the wall of said channel intermediate the ends of the latter and a valve chamber spaced from and aligning with said seat, the channel being of decreasing diameter from the inlet end to the valve chamber and of increased and uniform diameter from the exit of the valve chamber, a bodily slideable valve structure mounted in said chamber for coacting with said seat to close said channel, said structure depending at its lower end from said chamber, and a spring controlled angle-shaped pressure operated lever pivotally suspended from said intermediate portion forwardly of said hand grip and being slidably connected to the lower end 20 of said structure.

2. In a device for the purpose set forth, a casting including an intermediate portion, a forward end portion and a rear end portion arranged in depending relation with respect to said intermediate portion and providing a hand grip, said casting being formed with a channel from end to end thereof, a valve seat on the wall of said channel intermediate the ends of the latter and a valve chamber spaced from and aligning with 25 said seat, a lip depending from the top of the channel and partially closing the valve chamber, a bodily slideable valve structure mounted in said chamber for coacting with said seat to close said channel, said structure depending at its lower 30 end from said chamber, and a spring controlled angle-shaped pressure operated lever pivotally suspended from said intermediate portion forwardly of said hand grip and being slidably connected to the lower end of said structure, said intermediate portion being formed with a web 35 intermediate its ends from which said lever is suspended, said web being spaced inwardly from the sides of said intermediate portion.

3. In a device for the purpose set forth, a casting including an intermediate portion, a forward end portion and a rear end portion arranged in depending relation with respect to said intermediate portion and providing a hand grip, a perforated web depending between the intermediate 45 and rear portions, said casting being formed with a channel from end to end thereof, a valve seat on the wall of said channel intermediate the ends of the latter and a valve chamber spaced from and aligning with said seat, a bodily slideable valve 50 structure mounted in said chamber for coacting with said seat to close said channel, said structure depending at its lower end from said chamber, and a spring controlled angle-shaped pressure operated lever pivotally suspended from said intermediate portion forwardly of said hand grip and being slidably connected to the lower end of said structure, elongated slots for the spring in adjacent portions of the grip and lever, said lever having a bifurcated slotted end portion for straddling the lower end of said structure and through which extends the connecting means between the lever and said structure, said lever having a pair of spaced apertured ears intermediate its ends for straddling said web and through which and 65 the web extends the pivot for the lever.

4. In a device for the purpose set forth, a casting including an intermediate portion, a forward end portion and a rear end portion arranged in depending relation with respect to said inter- 70

mediate portion and providing a hand grip, said casting being formed with a channel from end to end thereof, a valve seat on the wall of said channel intermediate the ends of the latter and 5 a valve chamber spaced from and aligning with said seat, the channel being of decreasing diameter from the inlet end to the valve chamber and of increased and uniform diameter from the exit of the valve chamber, a bodily slideable valve structure mounted in said chamber for coacting with said seat to close said channel, said structure depending at its lower end from said cham- 10

ber, and a spring controlled angle-shaped pressure operated lever pivotally suspended from said intermediate portion forwardly of said hand grip and being slidably connected to the lower end of said structure, the controlling spring for the lever being arranged between the latter and the front of said end portion, said spring having oppositely disposed end portions slidably engaging in the rear face of the lever and front face of the rear end portion. 10
